UNITED STATES PATENT OFFICE.

ROBERT W. SCOTT, OF BOSTON, MASSACHUSETTS.

MECHANISM FOR KNITTING UPON TRANSFERRED FABRIC SECTIONS.

1,150,547.

Specification of Letters Patent.

Patented Aug. 17, 1915.

Continuation in part of application Serial No. 748,070, filed February 3, 1913. This application filed December 18, 1913. Serial No. 807,535.

To all whom it may concern:

Be it known that I, ROBERT W. SCOTT, a citizen of the United States, and resident of Boston, in the county of Suffolk and State of Massachusetts, have invented certain new and useful Improvements in Mechanism for Knitting Upon Transferred Fabric Sections, of which the following is a specification.

10 My invention relates to means for rendering more certain the transfer of a previously knitted section to a machine for knitting a part or all of the remainder of a plain fabric article, such as a stocking, and to means for causing the knitting of the article upon the transferred fabric to be begun with certainty, and with as few and simple hand operations as possible.

One object of my invention is to provide 20 devices for preparing the knitting machine for transferring a previously knit section of fabric such as a rib-top by hand, and for insuring the beginning of knitting by the machine in a certain manner, without intervention by the operator.

In the accompanying drawings, Figure 1 30 is a vertical central cross-section through a sufficient part of an automatic circular stocking-knitting machine to illustrate the application of my new devices; Fig. 2 is a plan partly in section on the line 2—2 of Fig. 1; Fig. 3 is a partial front elevation of the machine showing the cam or pattern shaft; Fig. 4 is a diagram development of the pat-

tern drum; Fig. 5 is a vertical section on the line 5—5, Fig. 6, on an enlarged scale, illustrating the position of a needle, a web-holder and a transfer quill during the transfer operation; Fig. 6 is a horizontal section 40 on a large scale taken on the line 6—6 of Fig. 3, showing the webholders, the needles and the web-holder guide ring; Fig. 7 is a diagram development of the needle cams illustrating the level position of the butts 45 of the needles; Fig. 8 is a perspective illustrating one construction of the web-holder guide-ring; Fig. 9 is a view similar to Fig. 4 showing a modified device; Fig. 10 is a side elevation of a form of web-holder employed in connection with the construction 50 of Fig. 7; Fig. 11 is a plan view of the top

of the latch ring; Fig. 12 is a diagram development showing the needles, the web-holders, the needle cams, and the new yarn; Fig. 13 is an enlarged diagram plan at the 55 yarn feed point, showing the needles, and the needle deflector; Fig. 14 is a detail section on the line 14—14 of Fig. 11 on an enlarged scale; Fig. 15 is a detail perspective of the belt-shipper cam; Fig. 16 is a 60 detail section showing the modification of one of the yarn guide actuating cams; Fig. 17 is a detail illustrating the use of a certain form of needle.

I have shown my new devices in connection with a hosiery knitting machine having a revoluble needle cylinder 260 splined on and driven through the sleeve 251 central with a bevel gear 30, suitably mounted to be driven by a bevel gear 31 (Fig. 3) in a depression of the bed or table D, upon which the stationary parts of the knitting head are mounted. The needle cylinder 260 is provided with a web-holder bed 295 attached to its upper end, having grooves for 70 guiding a series of web-holders 290 for operation by a web-holder cam ring 301, in radial planes passing between the independently movable needles n, held in longitudinal grooves, which may be formed by the inserted walls 261, on the surface of the cylinder 260. The needles n are divided into a set having long butts and a set having short butts, for the usual stocking knitting purposes.

Cooperating with the needles and the needle cylinder a relatively fixed cam ring 271 is suitably mounted, and equipped with cams having an idle ledge or level 4, Figs. 7 and 12. The ring 271 is cut away at one 90 point to provide slopes 5, 5 centrally between which center cams 8 and 9 are mounted, for instance on a standard 355, Fig. 1, attached by screws, as shown, to the ring 271, the cams 8 and 9 preferably being level 95 with the ledge 4. The cam ring or cylinder 271 is thus provided with cams defining two horizontal planes, between which there is a free level path for the needles. In the absence of the stitch cams about to be described a needle displaced vertically within the limits measured by the slopes 5, 5, or

the retracting slopes of the top center cam 8, will be returned to said level upon movement of the needle carrier relatively to the cams. The level so defined is intermediate of the extremes of the movement given to the needles during normal knitting.

- Working between the slopes 5 and the sloped ends of the cam 9 stitch cams 6 and 7 are mounted, for instance upon a half-ring or segment 370, Fig. 2, which is guided for radial movement with respect to the needle cylinder and cam ring on the plane central of the cams 8 and 9. I prefer to employ for guiding the segment 370 parallel slots 371 formed in a horizontal flange of said segment to receive shouldered hold-down screws 369 taking into the bed-plate of the machine, and a gib or key 372 sliding in a key-way formed in the bed D, for instance as shown, central on the plane of Fig. 1. The segment 370 is held toward the center of the needle cylinder by the spring 379 housed in shallow bores in said ring and in a post 401 erected on the bed D at the back of the machine.

In machines of the class which I have illustrated, the needles n are frictionally held in their grooves, for instance by laterally bending the needles, and it will be understood that the purpose of permitting the cams 6 and 7 to be removed is to bring the needles to a level in order to enable them to mate with the quills of a transfer cup or ring T, Fig. 5, upon which a piece of fabric such as a rib-top to be transferred is impaled loop by loop, which transfer ring may be such a structure as is familiar in the prior art.

Prior to the beginning of a new series of operations for another stocking or garment section, the knitting upon the previous garment will have ended, for instance by the removal of the knitting yarn from operative contact with the needles. Means for this purpose may comprise a thrust bar 460^c guided at one end in a comb 462 fast on the upper end of the standard 401, and at the other end resting against a fixed stud 450 attached to the machine frame and guided in a comb 451 attached to said stud.

The rounded lower end of the thrust bar 460^c rests against and is held by gravity toward the surface of a pattern drum 120, mounted to rotate on the stud 76, which is connected by a gear train 122, 123 to one end of the cam shaft 80, Fig. 1, intermittently actuated during the automatic knitting of an article by means of a rack wheel 81 and a pawl 82 under the control of a pawl-controller 83, positioned by lugs on a pattern chain 85, which pattern chain is intermittently advanced throughout the movement of the machine. Cam shaft 80 carries at one end a belt-shipper cam 106 coöperating with a lug 114 on a belt-shipper 100, to

cause the belt to be shifted from the active pulley 47 to the idle pulley 43 once during each revolution of the shaft 80 and the drum 120. Said bar 460^c coöperates at its lower end with a cam 503 carried by the pattern drum to move by contact with its upper end a yarn guide F pivoted at 554 in an upright extension 555 straddling a radial slot in the latch guard ring 300, which latch guard ring has an opening 75 slightly larger than the diameter of the circle of needles, and is held concentric with the needle cylinder by a mounting comprising a pivot 552 in the post 401.

The yarn guide F will usually be one of several like guides having similar actuating means, of which I have shown but one for clearness. When more than one is in use, all but one may be held in an upward idle position by suitable cams 503^a, 503^b, etc., placed similarly to the cam 503 in the drum 120 at the approaching end of knitting, or all of said guides F then in an operative position may be simultaneously elevated to remove all yarns from the needles. Elevation of the bar 460^c for instance will elevate the active yarn guide F from its active or yarn-feeding position of rest, shown in Fig. 1, on the throat plate 559 bridging the slot in the latch ring, so as to bring its inner end above and within the needle cylinder. This movement of the yarn guide F made against the stress of a spring f between said yarn guide and the pivot 552, will occur at the end of knitting one article or section. The elevated yarn guide F will then guide the yarn which it has been supplying toward the inside of the needle cylinder and upon the upper surface of an internal plate 602, supported by an extension 601 screwed to the latch guard ring, which plate carries a yarn cutter comprising a fixed blade 614, and movable blade 613, actuated by a vertical slide 608, in turn operated by a horizontal lever 611 pivoted at 610 on the latch guard ring, the outer end of which lever rests above a thrust bar 460^e similar to the bar 460^c, which thrust bar 460^e may be actuated by cams 506 suitably placed on the pattern drum 120.

A yarn thrown to the interior of the needle cylinder will be guided near the upper surface of the plate 602 by a fixed guide 604, and clamped upon said upper surface by one end of a lever 606 pivoted on a stud 607, actuated by a spring 609 upon the upward movement of the cutter, its other end taking under pin 603 entering the cutter slide 608, to open the clamp when the cutter slide 608 is depressed.

The latch guard ring 300 and its attachments, including the internal yarn guiding and clamping member 602, the yarn cutter, its actuating lever 611, the yarn guide or guides F, etc., may be swung about the pivot 130

552 to the position indicated in dotted lines in Fig. 1 in order to permit access to the heads of the needles for the transfer operation. This removal of the latch guard ring 5 300 and its attachments is made by hand, after the last yarn guide F in work has been thrown to its upper and inner idle position, and the cylinder rotated at least one revolution with the needles and web-holders in 10 action, to cast off the fabric from the needles; and after the yarn has been clamped and cut, and the machine stopped.

The machine so far as described above might well be for the purposes of certain 15 combinations claimed herein, any knitting machine of the prior art having independently movable needles, independently movable web-holders, an actuated yarn guide, and a pattern actuated stop mechanism. I 20 prefer, however, to employ the devices about to be described in connection with the particular machine chosen for illustration. I do not herein claim the said machine, which is described and claimed in my application 25 Serial No. 746,070 filed February 3, 1913 (of which this application is in part a continuation) except as to those parts and combinations of parts pointed out in the appended claims.

30 The devices now to be described are in aid of a rapid and certain transfer and the beginning of subsequent knitting.

So far as I am aware it has heretofore been necessary, in order to effect the transfer of a rib top or other previously formed fabric to the needles of a circular independent needle machine not only to level the needles but to provide some sort of support for the needles when level, to enable them to 35 maintain their gage or distance apart, and so mate with the quills q of the transfer ring T. Usual means for this purpose have comprised mechanism for leveling the needles upon a comparatively low path in a 40 special groove of the cam ring, in order to bring the needles to a low position in the cylinder, to enable the ends of the grooves in the cylinder to support them at a point 45 near their heads; or the needles have been 50 lifted away from their knitting cams, or above the normal level of their knitting cams into an elevated path with respect to the needle cylinder, which is thereafter 55 lifted to carry the verge or edge of the needle cylinder into a plane to support the heads of the leveled needles. In the former case, undue complexity of the cam ring and 60 obstruction of space thereon valuable for other purposes is necessary; while in the latter case means must be provided for preventing movement of the needles with the cylinder when it is elevated, in addition to the means permitting and for effecting an 65 abnormal relation of the needle-cylinder and the cam-ring at the time of the transfer.

In the machine I have selected as a preferred instance, the level of the ledge 4, and of the top of the bottom center cam 9 is that at which the needles are at the tuck point, the points of their latches not being lifted 70 above the plane determined by the upper level portion 291 of the web-holders 290. This is the natural level of the needles, occupied by them during intervals between knitting movements. I now utilize this natural level for effecting the transfer. In order to automatically cause all of the needles to reach the said level, I move the stitch cams 6 and 7 outwardly between two successive knitting operations, leaving the 80 center cam 8 in its fixed operative position. The center cam 9, while useful as a guard and positioning cam for needles moved by cam 8, is not essential, and I may not provide it in some cases. In one construction 85 for removing cams 6 and 7 the gib or key 372 is provided with extensions 373 bored to receive a removable pin 374, which may be held in place by set screw 375.

The extensions 373 and the pin 374 together constitute a yoke surrounding the thrust bar 460 which is provided with a cam lug 46 normally out of contact with the pin 374 in the extensions 373, but which may be brought against the said pin to move the segment or half-ring 370 and the attached stitch cams 6 and 7 radially outward with respect to the center of the needle cylinder whenever a cam 121 on the pattern drum 120 passes under the lower rounded end of 100 the bar 460, which may be cut off at the top as shown in Fig. 1.

The needle cylinder, in order to level the needles, may be rotated after the cam 6 and 7 have been removed, either prior to the 105 stoppage of the machine, or after it has stopped. In either case the cam 121 will remain under the thrust-bar 460 during this rotation which will be of an extent of at least one-half of the angular magnitude of 110 the extremes of the slopes 5, 5, to enable the center cam 8 and one of said slopes respectively to bring the needle butts to the level of the ledge 4. I prefer, however, to level the needles automatically prior to the stoppage 115 of the machine as an incident of the end of the operation upon a prior article.

Referring now to Figs. 1 and 4, the pattern drum 120 will at the approaching end of the article be brought to a position at 120 which the cam 121, the cam 503, and the cam 506 are about to encounter their respective thrust bars 460, 460^c, and 460^e. Indications upon the pattern drum, which have been active prior to this time may comprise 125 means to move thrust-bars similar to bar 460, or other indicating elements, to control the operation of a switch cam, of a widening picker or pickers, of yarn changing yarn guides, and of connections 281 operating 130

through the pins 256, and column 280 to alter the length of the stitch, as well as other mechanisms governing the production of fabric, such as the leg, heel, foot and toe 5 of a stocking, for instance as in the machine of my said application Serial No. 746,070.

Referring now to Fig. 1, the location of the cam 121, the cam 503, the cam 506, etc., with respect to the drum 120, the gear train 10 122, 123, the cam 80 and the belt shipper cam 106 (Figs. 3, 4 and 15) is such as to bring the face of the cam 106 active to stop the machine in line with the middle part of the cams 121 and 503. Movements are imparted to the shaft 80 through the rack 15 wheel 81 and the pawl 82 at intervals of a definite number of revolutions of the needle cylinder 260. The movement of the pattern drum 120 which determines the passage of the cams 121, 503, etc., under their respective thrust-bars will therefore occur prior to the stoppage of the machine by the action of the cam 106, and the needle cylinder 260 will rotate through a predetermined extent 20 (say from one to four revolutions) after the cam 503 shall have acted upon the thrust bar 460° to elevate the yarn guide F to remove the yarn from the work; after the cam 121 shall have actuated the thrust bar 460 25 to move the half ring 370 to its outward position, and after the cam 506 shall have actuated its thrust bar and the yarn cutter and clamp 613, 614 and 606 to cut and clamp the yarn, now thrown above and inwardly 30 of the needles, before the machine comes to a stop. The revolution of the needle cylinder 260 after the actuation of the bar 460 and the withdrawal of the stitch cams will have caused the needles to come to a level 35 corresponding to that of the ledge 4.

I prefer to form the cam 106 shown in Figs. 3, 4 and 15 to coöperate with the lug 114 of the belt-shipper slide 100 to stop the machine at the end of its cycle, as an adjustable attachment of the shaft 80; for instance by mounting it on the face of the speed changing cam 102 by screws taking 45 through slots 106^a. Said cam 106 is provided with a step 106^a on its leading face, to permit a halt of the belt upon its passage 50 from the high-speed pulley 47, at the intermediate-speed pulley 42, to slacken speed prior to stoppage by shifting the belt on the idle pulley 43. The belt may remain on 55 pulley 42 between two successive forward movements of shaft 80 and during several revolutions of the knitting head. The pulley 47 may be geared to the main shaft 32 through an increasing gear train, as in the 60 machine of my said application. Cam 106 is also provided with a step or level 106^b of a height to position the belt on the intermediate-speed pulley 42. When shipper 100 is moved to the right against the tension of 65 a spring 110 by the highest part of cam 106,

a gravity latch 112 taking against a projection of lug 114 locks the shipper against farther movement to the left.

The high part of the cam 106 is arranged upon the shaft 80 so as to come within the angle swept by the lug 114 under a forward impulse of pawl 82. This causes the shipper 70 100 to move to a position to stop the machine just prior to the completion of the movement of the cam 106 in which position 75 the shipper is locked by the latch 112. Momentum of the machine is sufficient to complete the stroke of the pawl 82, carrying the high part of the cam 106 beyond the lug 114, and leaving the machine ready to be 80 started at a slow speed upon releasing said latch 112.

In the machine as shown in the drawings it will be noticed that the needle grooves proper of the needle cylinder do not extend 85 above the grooves 262 in the flange upon which the web-holder bed 295 is mounted. This is to enable the inboard ends of the web-holders 290 to be guided in a guide ring or nosing 297, substantially of the 90° structure patented to Geo. D. Mayo No. 726,178, April 21, 1903, comprising an internal groove, the upper and lower walls of which guide the lower arms 292 of the web-holders to accurately position the knocking- 95 over surface formed by their upper arms 291 in a plane perpendicular to the needles, and in which the web-holders are spaced by the walls 310 (Fig. 8) left between radial longitudinal slots 311 milled in the outer face 100 and through the upper end of said ring 297. As shown in said patent, the grooves 262 of the needle cylinder 260 might well be carried to a point nearer the heads of the needles, but ending beneath the web-holders, while still retaining the advantages of the ring 297, but I prefer to proportion the parts substantially as shown in Fig. 1, leaving the considerable free clearance space 298 between the web-holder bed 296, the outer 105 face of the ring 297, and the faces of the needles when they are in position. When the grooves 262 end either at the point shown in Fig. 1, or at the higher point defined by the bottoms of the web-holders, 110 these walls are still too far beneath the heads of the needles, when they are positioned as shown in Fig. 1, to afford sufficient lateral support to the needles to space them for the transfer ring, especially in the case 115 of machines of fine gage, in which the needles may be very thin and resilient, and in which individual needles may frequently be found to have impressed bends, causing them to be misspaced when much project- 120 ed beyond their guiding grooves.

Referring now to Figs. 5 and 6 the web-holders 290 are in common practice thin, rigid sheet metal structures, occupying less than the space between the needles, as shown 125

for instance in the section Fig. 6. The web-holders may be reduced in thickness at those parts coming in contact with the yarn, as at 293, Fig. 5, in order to give more room for the yarn between two adjacent needles. The necessary position of the web-holders between the needles implies that they shall pass through a space which would otherwise be occupied by the guide walls for the needles.

In order to provide a guide for the needle against lateral strains which shall be effective upon it at the highest point possible, I form in the face of the ring 297 shallow guide grooves 312, which may be substantially one-half the radial thickness of the needles, as shown in Figs. 6 and 8. The relatively thin web-holders may thus be guided in a position central between the needles by the grooves formed by walls 310, while the needles themselves are supported in a shallow groove 312 as far up as the plane 313 near the upper level 291 of the web-holders (see Figs. 5 and 8).

So far as I am aware the needle-groove has in prior machines always stopped short of the position of the web-holders, which have been provided with slots in a part of the needle carrier not constituting walls defining the needle grooves. With web-holders of any practical thickness, their guide slots consume a great part of the space between the needles, leaving little room for walls to define a needle groove. But there is, even in fine gage machines, an appreciable difference between the space separating the needles, and the necessary thickness of a web-holder, and I find that by making the grooves 312 sufficiently deep, I may efficiently guide the needle. Such shallow grooves are practicable to mill, whereas a deeper groove would weaken the metal to a degree causing it to collapse during manufacture. The needles are held in engagement with the grooves 312 by the usual spring bands 263, as shown in Figs. 1 and 5. The support of the needles laterally by this device is sufficient to enable the accurate engagement of quills *q* of the transfer ring *T* when the needles are in the tuck position shown in Figs. 1 and 5.

I may accomplish the same ends by the modified construction shown in Figs. 9 and 10, in which the guiding grooves 311 for the web-holders 290^a are made of a width taking all the space between the needles *n*, the web-holders 290^a being of a thickness to fill the grooves, and to themselves space the needles. In order to permit the needles to operate without interference with their latches of the yarn loops I form the said web-holders with a reduced portion 294 which may be substantially of the proportions shown in Fig. 10. It will be understood that the thicker parts of the web-

holder 290^a extend high enough upon the needle to support it when it is in the position shown in Fig. 5, so that the head of the needle shall not stand laterally out of its properly spaced position. The reduced portions 294 are of an extent to permit the free swinging movement of the needle latches during knitting.

As shown in Fig. 10 the reduced area 294 may extend through substantially only the upper half of the vertical dimensions of the web-holder, leaving the full thickness to guide the needles throughout the lower half, thus effecting the lateral guidance of the needles as far up as the level of the point 295, which is sufficient for the purpose required.

So far as described the machine has been provided with devices for leveling the needles and for spacing them to receive the transfer quills when level at their normal position on the ledge *l*, and the machine has been stopped in this position. A transfer ring loaded with a new fabric section impaled loop by loop upon each of its points being provided, the operator of the machine will as a hand operation lift the latch ring, place the transfer ring in engagement with the needles in the position shown in Fig. 5, turn the fabric section down within the needle cylinder, and then remove the transfer ring, leaving the loops on the individual needles. This being done, the latch ring is returned to its normal position shown in full lines in Fig. 1.

The manual operations above mentioned may be rapidly performed and one of the objects of my invention is to avoid any further manipulation. I therefore provide that the machine shall automatically begin the knitting of the new fabric when started by the operator. Starting is done by lifting the belt-shipper latch 112, whereupon belt-shipper slide 100 moves to the left, Fig. 3, as far as permitted by the level 106^b of the stop cam to place the belt on the pulley 42, to drive the machine at an intermediate or slow speed. The next movement of the shaft 80 and the drum 120 therewith will cause the cam 121 to pass from under the thrust bar 460 to release the half-ring 370, spring 379 causing the stitch cams 6 and 7 to move toward the center of the needle cylinder, and into a position to engage and actuate the needle butts. Owing to the unbroken extent of the still level needles, these cams cannot enter upon the needles, or pass to their extreme inward position except by passing first upon the periphery determined by the level line of short butt needles, from which position the advancing surface of the leading stitch cam 7 may engage so much of the butt of the leading long butt needle as projects beyond the periphery determined by the short butts. This leading

long butt needle, shown at n' in Fig. 12 will therefore be the first needle elevated to clear the loop of the transferred rib top below its latch, and the first needle to pass down the active slope of the stitch cam 6, the remaining long butt needles following it in order. When sufficient of the long butt needles have passed the cams there are no longer any short butt needles opposite the faces of the cams and the spring 379 will then move the half ring and the attached cams 6 and 7 to their innermost position in which they can engage and move all of the needles. This will occur when the last short butt needle n^{220} , Fig. 12, has passed off the face of the cam 6.

It is necessary to effectively supply needle n' and the needle following it with yarn. Merely permitting yarn to be fed to the needles at any point when the machine is starting upon a fresh operation, with a new rib top on the needles, is not always sufficient to secure the taking of the yarn by the leading long butt needle n' . This is due to the fact that the needles immediately preceding the needle n' and constituting the following end of the short butt series, of which the needle n^{220} is the last needle, are still in an elevated position. However close the end of the yarn guide may be to the circle swept by the hooks of the needles, the yarn supplied will, by the rotation of the machine, lie upon a line tangent to the circle at a point well beyond the yarn guide.

Referring now to Fig. 12, it will be seen that the withdrawal movement of the needle n' and those following it begins upon their encounter with the down-going slope of the cam 6 at a point very near the vertical plane of the yarn guide. A yarn merely supplied to the needles at any time prior or during their rotation before the described separation of the leading long butt needle from the following short butt needles will therefore take the path illustrated by the dotted line y' in Fig. 12, and the leading long butt needle will not be supplied.

It has heretofore been customary for the operator to interfere with the yarns upon the needles, or with the needles, in machines employed for knitting upon rib-tops, in order to secure the certain taking of the yarn by the leading long butt needle when the said needle is first caused to enter the stitch cams. In order to avoid this operation, which consumes time and requires skill, I may secure the taking of the yarn by giving to the leading long-but needle n' a permanent outward bend, as shown in Fig. 17, so that when projected it will stand forward out of line with the other needles. For machines capable of knitting plated fabrics I prefer, however, to employ the following devices.

Upon the plate 602 an upright rigid post 705, see Figs. 11 and 14, is provided, which carries the sleeve 706 having a lug 707 in which is a horizontal bore 708, to receive an internal needle cam-arm 700, which may be made as a wire arm having a bend 701 to contact with the needles at a point in the neighborhood of the vertical plane of the leading end of the active stitch cam 6. The cam arm 700 is adjustably held in place by a set screw 702. The sleeve 706 is under the influence of a spring 709 held at one end by the set screw 702 and adjustably held at the other end by a bore 710 in a washer 711 held on the top of the post 705 by the screw 712. The spring 709 tends to remove the cam-arm 700 from the position shown in Figs. 11 and 13, in which position it is adjusted to contact with and move a few of the needles outwardly substantially into contact with the inner face of the latch ring 300, as shown in Fig. 13, in which position the needle hook is well over a yarn taking the path y' .

The sleeve 706 is provided with a thumb piece 715 and with a lug 716, having a face radial with the post 705 to engage the outer end of a stepped latch 717 mounted on the same pivot 607 as the yarn clamping lever 606, which latch stands over the lever 606 as shown in Figs. 1 and 11. The outer end of the latch 717 when in engagement with the radial face of the lug 716 will hold the cam-arm 700 in the described position shown in Fig. 13 but when the latch 717 is elevated as by lifting the lever 606 the sleeve 706 is permitted to rotate through a short distance under the influence of the spring 709 until the lug 716 brings up against the step in the latch.

When the device is in use the operator will set the lug 716 opposite the end of the lever 717 by means of the thumb piece 715 at the time of lifting the latch ring. This may be done without necessitating an extra movement of the hand. When the latch ring is restored to its normal position after the rib top has been transferred, all of the needles will be engaged and moved outwardly as shown in Fig. 13 when the machine is rotated and this will continue to occur until the latch 717 has been moved.

The drum 120, as described above, having been actuated to move the thrust bar 460 to return the knitting cams to a position from which they pass into their active position when permitted by the butts of the needles, a further movement of the drum permits the end of the cam 503 to pass from the thrust bar 460 to place the yarn guide F in its operative position shown in Fig. 1. The movement which causes the cam 121 and the cam 503 to leave the ends of their respective thrust bars may be the same movement, but this is not essential. The cam 503 will be so placed with respect to the surface of the

drum 120 and the locus of its angular movement with respect to the rotation of the needle cylinder as to cause the yarn guide to drop into its operative position past the 5 heads of the elevated needles so as to give the yarn to a predetermined part of the following end of the short butt series preceding the long butt needle n' first to be actuated. As shown in Fig. 12, the yarn has 10 been dropped in between needles n^{215} and n^{216} . The inner end of the yarn y , which was cut at the end of the last operation, now rests under the clamp 606, from which it will be withdrawn by the rotation of the 15 machine acting through the needle n^{216} , after the needle n' shall have knit. The cam arm 700 has secured the taking of the first loop by the needle n' in the manner explained.

20 I thus secure leaving a short end only of yarn attached to the fabric at the beginning of the plain knitting, which end interlocks with a yarn of a later course at a sinker wale at the point where it entered the 25 needles, such as the sinker wale between the knit wales from the needles n^{215} and n^{216} . This result is due to the yarn of the second course overlying the yarn of the first course at the needles intervening between 30 the entering point and the needle n' , the yarn of the second course being taken into the needle hooks and the yarn of the first course being cast off unknit except by the needle n' and those following it. This 35 engagement of the entering yarn with the fabric at a point near the initial knit loop serves to prevent either the knitting movement of the needle n' or subsequent strain upon the fabric from opening the first plain 40 loop into a loose loop or eyelet hole, as is sometimes the case when the first-actuated needle is the first to engage the yarn passing to it from a point within the circle of needles, the yarn in the latter case having 45 no frictional engagement with the needles or fabric on one side of the knit loop.

Whether or not employing the bent needle n' of Fig. 17 or the cam-arm 700, I find it desirable to deliver the entering yarn to the 50 needles with as great accuracy as may be secured. Under some circumstances I find it desirable, for instance to apply the yarn between the needle n^{220} and the needle n' , thus avoiding the difficulty of the yarn lying 55 upon a tangent to the circle of needles above explained, without attempting to avoid the loose initial loop, which is not detrimental in many fabrics, and may not occur in fabrics knit from yarns of a high frictional 60 quality. It will be understood that when yarn is applied to a few needles in advance of the needle n' in conjunction with either the bent needle of Fig. 17 or the use of the arm 700, it is not necessary to provide for 65 its accurate entrance within a margin of

several needles, but that when it is required to feed the leading high butt needle as the first needle, great accuracy is essential. I may therefore provide the machine with a cam 503 constructed as shown at 503^a in Fig. 16. Said cam is fast upon the drum 120 in the same position as before, but its length is reduced by cutting off that end of it which last passes under bar 460^c, as shown at a , Fig. 16. The cam is undercut 75 at b to receive an adjustable spring extension c , slotted to receive a screw d for adjustment longitudinally of the body of the cam and adjustable radially of cam 120 by a headless screw e . The drum 120 may be 80 bored out as shown at f to receive the head of the screw d .

The adjusted height with respect to the drum 120 of the extension c of the cam 503^a is such as to cause the bar 460^c, at the time 85 of the passage of the cam 121 from beneath its thrust bar, to permit said thrust bar 460^c to fall far enough to hold the yarn hole in the end of the yarn guide F just above needles traveling at the level of the ledge 4. 90 From this position, in which the yarn passes above and very close to the hooks of the needles, a minimum movement of the yarn will secure its entrance between and taking by the needles. This movement occurs when 95 the extension c passes from beneath the bar 460^c, on the next rack of the drum 120, as described above in connection with the cam 503. The timing of the drop from the end of the extension c may be delicately adjusted by moving the extension c circumferentially and locking the screw d , while the vertical position of the yarn may be delicately determined by the screw e .

All of the described operations at the beginning of an article will have taken place 105 while the lug 114 is upon the intermediate level 106^b of the cam 106 and therefore while the machine is running at a slow speed. The next movement of the shaft 80 110 and the drum 120 will permit the lug 114 to come against the face of the speed-changer cam 102, to cause the belt to pass on the pulley 47, and the machine to attain 115 its full speed.

In order to avoid wear upon the needles, and a force tending to distort them side-wise during such times as they are lifted for the heel and toe, I may remove the cam arm 700 from the position shown in Figs. 11 and 13, to the dotted line position shown in Fig. 13, by lifting the latch 717 through the agency of the clamp 606. I may do this upon any movement of the drum 120 by providing a lug 506^a in the proper position, 120 which may be that at which the lug will act to move the clamp when the speed is increased, as shown in Fig. 4. The actuation 125 of the cutter and the elevation of the clamp arm 606 for this purpose will be of no effect 130

since there is then no yarn to cut, and since idle yarns held in the clamp 606 will be under no tendency to be removed therefrom when it is lifted.

5. What I claim is:—

1. In a knitting machine, a needle cylinder, needles, cams for moving the needles to knit, and means coöperating with the needles and cams to predetermine a cycle of knitting operations, in combination with means acting automatically to adjust said cams during the cycle and prior to the end thereof to bring each of said needles to a position intermediate of the extremes of its knitting movement to level the needles with respect to said cylinder.
10. 2. In a knitting machine, a needle carrier normally in position for knitting, needles, cams for moving the needles to an advanced and to a retracted position for knitting, in combination with automatic means for moving certain of said cams only out of contact with said needles at a predetermined time, to bring said needles automatically to an intermediate position with respect to the normally positioned needle carrier.
15. 3. A circular knitting machine having in combination needles, cam and needle carriers relatively rotatable in a relation in which said needles are at a normal level with respect to their carrier, a stitch cam for moving said needles out of said level to knit, said stitch cam being movable away from said needle carrier, and automatic means for moving said stitch cam away from said needle carrier at a predetermined time during operation of said machine, whereby to bring the needles to said normal level.
20. 4. A circular knitting machine having cam and needle carriers, and needles in said needle carrier, in combination with stitch cams, a mounting therefor movable away from said needle carrier, and an automatically operated connection for moving said mounting and stitch cams away from said needle carrier at a predetermined time during relative rotation in their normal relation for knitting of said needle and cam carriers, whereby to level the needles.
25. 5. A circular knitting machine having in combination relatively rotatable cam and needle carriers, and needles in said needle carrier, in combination with a mounting movable away from said needle carrier, stitch cams on said mounting and automatic means for moving said stitch cams into operative position and out of operative contact with said needles at predetermined times comprising a pattern surface, and a connection from said surface for moving said mounting away from and toward said needle-carrier during relative rotation of said carriers whereby respectively to render all of said needles inoperative and to resume their knitting movements.

6. In a circular knitting machine a cam carrier and a needle cylinder, needles in said needle cylinder, a segment on said cam-carrier movable toward and away from said needle cylinder, stitch cams on said segment, and an automatic operating connection for moving said segment and stitch cams to determine needle-leveling and knitting movements of said needles respectively comprising a pattern-actuated bar, and means for causing movement of said segment toward and away from said cylinder upon actuation of said bar.

7. In a knitting machine, a needle cylinder normally in position for knitting, needles therein, knitting cams for advancing and retracting the needles, means for leveling the needles and means for holding the needles in an evenly spaced relation with respect to said needle cylinder when in a normal position to receive a previously knit fabric on a line between their advanced and retracted positions.

8. In a knitting machine, movable needles, cams for moving the needles to knit, and means coöperating with the needles and cams to predetermine a cycle of knitting operations, in combination with means automatically acting during motion of the machine at the end of the cycle to cast the fabric from the needles, and means causing certain of said cams at a predetermined time thereafter to bring each of said needles to a position intermediate of the extremes of its knitting movement.

9. In a knitting machine, movable needles, cams for moving the needles to knit, and means coöperating with the needles and cams to predetermine a cycle of knitting operations, in combination with means acting at the end of the cycle to cast the fabric from the needles, means acting thereafter for rendering certain of said cams inoperative upon said needles to bring each of said needles to a position intermediate of the extremes of its knitting movement, and means acting thereafter to stop the machine.

10. In a knitting machine, independently movable needles, web-holders normally standing between the needles, knitting cams for advancing and retracting the needles, means acting to adjust said knitting cams to level the needles to receive a previously knit fabric on a line between their advanced and their retracted positions, with their heads projected beyond the web-holders, and means for causing the head of each needle to occupy a plane central between the adjacent web-holders.

11. In a knitting machine, needles, web-holders normally standing between the needles in a position to define a relatively fixed plane at which the old loop is knocked over the new loop, means for advancing and retracting the needles with respect to said

plane for knitting, means to cast off the fabric from the needles, and means acting on the needles to bring the heads of the needles into a plane parallel with the web-holders, 5 and between the knocking-over plane and the position of an advanced needle, acting at a predetermined time thereafter.

12. In a knitting machine, independently movable needles, web-holders normally 10 standing between the needles, knitting cams for advancing and retracting the needles and means for leveling the needles to receive a previously knit fabric, in combination with means for laterally supporting the 15 heads of the leveled needles.

13. In a knitting machine, independently movable needles, web-holders normally standing between the needles, knitting cams for advancing and retracting the needles 20 and means for leveling the needles to receive a previously knit fabric, in combination with means for laterally supporting the leveled needles at a point above the bottom edge of the web-holders.

25 14. In a knitting machine, independently movable needles, web-holders normally standing between needles, knitting cams for advancing and retracting the needles, and means for leveling the needles to receive a 30 previously knit fabric on a line between their advanced and retracted position with their heads projected beyond the web-holders, in combination with means for laterally supporting the heads of the leveled needles.

35 15. In a knitting machine, independently movable needles, knitting cams for advancing and retracting the needles and means for leveling the needles to receive previously knit fabric on a line between their advanced 40 and their retracted positions, and web-holders normally standing between needles, in combination with means at the intersection of the needles and web-holders for laterally supporting the heads of the leveled needles.

45 16. In a knitting machine, a needle carrier, and a series of needles, a stitch cam, and means to begin knitting comprising means to move a yarn into contact with the needles at a predetermined time, in combination 50 with means to cause the stitch cam to become operative upon the needles at a predetermined later time.

17. In a knitting machine adapted for knitting a section of fabric upon a previously 55 knit section transferred thereto, a needle carrier and a series of needles, a stitch cam, means to begin the operation comprising devices for placing a yarn on the needles in a predetermined relation to the 60 needles, in combination with means to cause the stitch cam to become operative upon the series of needles at a predetermined point with relation to the position of the yarn.

18. In a knitting machine, adapted for

knitting a section of fabric upon a previously 65 knit section transferred thereto, a needle carrier and a series of needles, a stitch cam, means to begin knitting comprising a yarn guide, and means for moving the 70 yarn guide at a predetermined time to place a yarn in contact with the needles, in combination with means to cause the stitch cam to become operative upon the needles at a predetermined and later time.

19. In a knitting machine adapted for 75 knitting a section of fabric upon a previously knit section transferred thereto, a needle carrier and a series of needles, a stitch cam, means to begin the operation comprising means for placing a yarn in contact with 80 a predetermined part of the series of needles, in combination with means automatically to cause the stitch cam to become operative upon a predetermined needle and the following 85 needles of the series.

20. In a knitting machine, needle and cam carriers, needles, a stitch cam and means for entering said cam into and for withdrawing said cam from contact with any of the needles at predetermined times during relative rotation between said needle and cam carriers, to level the needles, in combination with devices for stopping the machine at a predetermined time after said cam is withdrawn.

95 21. In a knitting machine, driving mechanism including automatic speed-changing devices, a stitch cam and means for holding said cam out of contact with any of the needles, and means for entering said cam 100 into contact with the needles at a predetermined time during the operation of the machine at a reduced speed.

22. In a knitting machine, needle and cam carriers, needles, a stitch cam and means for entering said cam into and for withdrawing said cam from contact with the needles at predetermined times during the operation of the machine, and devices for stopping the machine at a predetermined time after said 105 cam is withdrawn, in combination with means for predetermined a reduced driving-speed for the machine when it is again started.

23. In a knitting machine, needle and cam carriers, a stitch cam and means for withdrawing the stitch cam from contact with the needles at a predetermined time in the operation of the machine, and for thereafter stopping the machine, means to supply yarn 120 to the needles, means to restore the stitch cam to an operative position during another operation of the machine and means to render the yarn supplying means operative and inoperative at predetermined times with relation to the times of the operative and inoperative position of the stitch cams.

125 24. In a knitting machine having inde-

pendently movable needles, devices for leveling the needles for transfer comprising needle - advancing and needle - retracting cams fixed relatively to their carrier, respectively for moving the needles into a position intermediate the extremes of their movement, in combination with stitch cams for moving the needles above and below said position, and means for removing said stitch cams from contact with the needles at predetermined times.

25. In a circular knitting machine, devices for leveling the needles for transfer, comprising a cam carrier having advancing and retracting cams thereon in a position to define a free level for the needle-butts with respect to said cam carrier, a stitch cam, and means to move said stitch cam radially out of contact with needles positioned at said level at predetermined times.

26. In a knitting machine, a needle carrier and needles, a cam carrier having fixed advancing cams and a fixed retracting center cam thereon in a position excluding a free level for the needle-butts with respect to said cam carrier, stitch cams coöperating with said center cam, and means to move said stitch cam out of contact with the needles during relative movement of said carriers to bring said needles to said level.

27. In a knitting machine, a needle carrier and needles in combination with devices for leveling the needles for transfer, comprising a cam carrier having separated fixed advancing cams and a fixed retracting cam thereon in a position to define a free level for the needle-butts with respect to said cam-carrier, stitch cams coöperating with said retracting cam, means to move said stitch cams out of contact with needles positioned at said level, and means for predetermining relative movement of the needle and cam carriers after said stitch cams have been moved.

45. 28. In a knitting machine, a cam carrier having fixed advancing cams and a fixed retracting center cam thereon in a position to define a free level for the needle-butts with respect to said cam carrier, a leading stitch cam having an advancing surface to encounter needles at said level and a following stitch cam having a depressing cam surface coöperating with said center cam, in combination with automatic devices acting 50 to move said stitch cams out of contact with the needles to permit them to be positioned at said level at a predetermined time.

60. 29. A knitting machine for knitting on transferred fabric having in combination a series of hooked needles, a yarn guide and means for initiating knitting upon said series of needles while they are level comprising means to operate the needles in series beginning at a certain needle, and means for

moving said needles laterally out of line at 65 the yarn feed point during the beginning of knitting, to secure the taking of yarn by the first actuated needle.

30. In a knitting machine a series of hooked needles, a yarn guide, means to cause 70 relative movement for knitting between said yarn guide and said needles, means to initiate knitting movements of the needles beginning at a certain needle, and a needle cam for moving needles laterally out of line 75 to place the hooks of the initially operative needles over the yarn in combination with means to render said needle cam inactive at a predetermined time.

31. In a knitting machine for knitting 80 upon transferred fabric, a series of needles normally level at the beginning of the operation, and means to cause knitting movements beginning at a certain needle of the series in combination with means to feed a 85 new yarn to the needles at a predetermined point in the series preceding said certain needle in the direction of knitting.

32. In a knitting machine, a series of needles normally level to receive a previously 90 knit fabric, in combination with means to knit a new fabric comprising means to cause knitting movements at a predetermined time, beginning at a certain needle of the series, and a yarn-guide active to feed the 95 new yarn to the level needles at a predetermined point in advance of said certain needle.

33. In a knitting machine for knitting upon transferred fabric, a series of needles 100 normally level at the beginning of the operation, and means to institute knitting beginning at a certain needle of the series, comprising means to feed a new yarn to the needles at a predetermined point in the series preceding said certain needle in the direction of knitting, in combination with means to move said certain needle and those 105 following it out of line into contact with the yarn.

34. In a knitting machine, a series of needles, means to bring the needles to a level, a stitch-cam, and means to move said cam into operative contact with the needles beginning at a certain needle; a movable yarn-guide, and means to render said yarn guide operative to feed a new yarn to the leveled needles, in combination with devices coacting with said certain needle and following needles to move them into contact with the 115 new yarn.

35. In a knitting machine, a series of needles, means to bring the needles to a level, a stitch-cam, and means to move said cam into operative contact with the needles beginning at a certain needle; a movable yarn-guide, and means to render said yarn guide 125 operative to feed a new yarn to the leveled

needles, in combination with a device co-
acting with said certain needle and follow-
ing needles to move them into contact with
the new yarn, and pattern controlled means
5 for rendering said device inactive.

In testimony whereof, I have signed my

name to this specification in the presence of
two subscribing witnesses.

ROBERT W. SCOTT.
